CHILD'S TOILET TRAINING FIGURE

Frances Bales Hill, 6100 Yolanda Drive, Fort Worth, Tex.

Filed May 11, 1960, Ser. No. 60,545

Term of patent 14 years

(Cl. D25—1)

Fig.1

Fig.2

Fig.3

Fig.4

Fig.5

I claim:

The ornamental design for a child's toilet training figure, substantially as shown.
